US00D600694S

(12) **United States Design Patent**
Sumii

(10) **Patent No.:** US D600,694 S
(45) **Date of Patent:** ** Sep. 22, 2009

(54) **ARITHMETIC AND CONTROL UNIT**

(75) Inventor: **Tetsu Sumii**, Tokyo (JP)

(73) Assignee: **Sony Corporation**, Tokyo (JP)

(**) Term: **14 Years**

(21) Appl. No.: **29/287,549**

(22) Filed: **Aug. 21, 2007**

(57) **CLAIM**

The ornamental design for an arithmetic and control unit, as shown and described.

DESCRIPTION

FIG. 1 is a perspective view of a first embodiment of an arithmetic and control unit showing my new design;

FIG. 2 is a front elevational view thereof;

FIG. 3 is a rear elevational view thereof;

FIG. 4 is a left side elevational view thereof;

FIG. 5 is a right side elevational view thereof; and

FIG. 6 is a top plan view thereof.

FIG. 7 is a perspective view of a second embodiment of an arithmetic and control unit showing my new design;

FIG. 8 is a front elevational view thereof;

FIG. 9 is a rear elevational view thereof;

FIG. 10 is a left side elevational view thereof;

FIG. 11 is a right side elevational view thereof; and

FIG. 12 is a top plan view thereof.

FIG. 13 is a perspective view of a third embodiment of an arithmetic and control unit showing my new design;

FIG. 14 is a front elevational view thereof;

FIG. 15 is a rear elevational view thereof;

FIG. 16 is a left side elevational view thereof;

FIG. 17 is a right side elevational view thereof; and,

FIG. 18 is a top plan view thereof.

The portions indicated in broken lines are for illustrative purposes only and form no part of the claimed design.
